UNITED STATES PATENT OFFICE.

WILLIAM L. BARTON, OF VANCOUVER, BRITISH COLUMBIA, CANADA, ASSIGNOR OF FORTY-FIVE PER CENT TO JOHN L. KERR, OF VANCOUVER, BRITISH COLUMBIA, CANADA.

OVERHEAD CARRIAGE.

Application filed August 5, 1921. Serial No. 490,123.

To all whom it may concern:

Be it known that I, WILLIAM L. BARTON, citizen of the Dominion of Canada, residing at Vancouver, in the Province of British Columbia, Canada, have invented certain new and useful Improvements in Overhead Carriages, of which the following is a specification.

This invention relates to an overhead carriage for a wire rope track line, the object of the invention being to provide a means operative from the winding engine for elevating the load to any desired height in relation to the carriage and for securing it at that desired position of suspension and for releasing it therefrom.

The invention is fully described in the following specification, reference being made to the drawings by which it is accompanied, in which:

Fig. 1 is an elevation showing the general arrangement of the track ropes in relation to the hauling engine and to the outer end of the track line with the carriage thereon.

Fig. 2 is a plan of the same.

Fig. 3 is a longitudinal section of the carriage to an enlarged scale on the line 3—3 in Fig. 4.

Fig. 4 is a plan of the carriage.

Fig. 5 is an enlarged detail of the clutch operating mechanism, and

Fig. 6 is a cross section of the same.

In these drawings 2 and 3 represent adjacent and parallel lines of a track rope on which the carriage with its load may run. At the outer end of the track this rope passes around a sheave 4 and the ends of it are connected to separate drums 5 and 6 of the hauling engine with provision whereby the drums may be simultaneously rotated in opposite directions to move the two lines 2 and 3 endwise in relation to one another.

On these track ropes 2 and 3 the carriage 7 is suspended on independent sheaves 8, 9 and 10, 11 which sheaves are mounted to turn freely on their axles secured in the side plates of the carriage. The rope 12 by which the load is elevated to the carriage and the carriage drawn inward toward the hauling engine passes over a sheave 13 mounted at the adjacent end of the carriage, and is anchored at 14 adjacent the midlength of the carriage, after passing around a sheave 15 at the outer end. The load is connected to a hook 16 suspended from a sheave 17 in

the bight or loop of the rope 12 between the sheave 15 and the anchorage 14.

The haul-back line 55 by which the carriage is drawn to the outer end of the track, or by which it is held while the load is drawn up to the carriage, is connected at 56 to the outer end of the carriage.

Between the sheaves 13 and 15 the hauling rope 12 passes over a grooved clutch bar 18 secured to the carriage. Above this fixed bar 18 is a grooved clutch bar 19, which is vertically movable to and from the fixed bar 18 by toggle links 20. The upper end of each pair of links 20 is pivotally connected at 21 to the frame of the carriage and the connecting pins 22 of the links are connected by bars 23 and 24 to a lever 25 fulcrumed at 26 to the carriage and connected at 27 by a link 28 to a cross head 29 endwise movable on slide bars 30 by the following mechanism.

To the cross-head 29 is rotatably connected one end of a screw 31, the axis of which is parallel to the guide bars 30. This screw 31 is carried in a nut 32 and a sleeve 33, the nut fitting the thread of the screw, and the sleeve fitting the tops of the threads with a feather 34 secured in the sleeve and movable in a featherway lengthwise cut in the screw. Both the nut 32 and sleeve 33 are rotatable in a bearing 35 secured to the upper side of the carriage frame 7, which bearing has thrust rings 36 fitting grooves in both nut and sleeve to prevent endwise movement of either in the bearing.

On the end of the nut 32, which projects from one end of the bearing 35, is held in a manner to be described a bevel gear 37, the teeth of which mesh with those of a corresponding gear 38 rotatably mounted in a bearing secured to the frame of the carriage. The gear 38 and consequently the nut 32 are rotated from the track wheel 9 of the carriage by an endless chain 39 around sprocket wheels secured to rotate with the track wheel 9 and with the gear wheel 38.

Similarly on the end of the sleeve 33 is frictionally held a bevel gear 40, the teeth of which mesh with those of a gear 41, rotatably mounted on the frame of the carriage, and an endless chain 42 drives this gear 41 by sprockets rotating with the track wheel 8 and the gear 41 respectively.

With this mechanism, if the track wheel 9 is rotated, it will rotate the nut 32 on the screw 31 and that nut, being prevented mov-

ing endwise by the rings 36 of the bearing, will endwise move the screw 31 in either direction according to the direction of rotation of the track wheel 9.

5 Again rotational movement of the track wheel 8, will, through the mechanism connecting it to the sleeve 33, and screw 31, rotate that screw and will therefore endwise move it through the nut 32.

10 As the carriage is moved in the direction of the arrow (C) along the track lines 2 and 3, while those lines are stationary in relation to one another, the track wheels 8 and 9 will be rotated in the direction indicated, 15 and by virtue of their chain and bevel wheel mechanisms, the wheel 8 will rotate the screw 31 and 9 will rotate the nut 32 in the same direction, so that no endwise movement will be imparted to the screw through 20 the nut to actuate the toggle clutch; but if one end 2 of the rope is wound up on its drum 5, while the other 3 is paid off from its drum 6, so as to move the lines 2 and 3 in opposite directions, the screw 31 will be 25 rotated to endwise move it to apply the toggle pressure on the clutch bar 19, and the nut 32 will be rotated in the opposite direction to endwise move the screw in the same direction and the screw being free to 30 move endwise in the sleeve, the endwise movement of the screw will be doubled to apply the clutch.

Obviously, if the lines 2 and 3 are moved in opposite directions to what is shown by 35 the arrows (A) and (B), the screw will be moved in a direction to release the clutch. These conditions will prevail whether the carriage is moving or is stationary on the track ropes 2 and 3.

40 To avoid undue pressure being imposed on the toggle mechanism, the bevel gears 37 and 40 are frictionally connected to the nut 32 and sleeve 33. The means by which this is done is shown in Fig. 5, where the nut 45 and sleeve are shown as provided with an integral collar 45 with a friction ring on each side of it. On the opposite side of the collar to the gear wheel is a ring 46, and the gear wheel and ring 46 are drawn together 50 on the collar and friction rings by bolts 47 having springs on the nuts that the pressure which is imposed may be regulated to what is desired.

55 In use, the carriage is drawn out toward the outer end of the track line by a haul-back line 55, and the load block 16 is lowered to lift its load. After connection to the load the hauling line 12 is drawn in to elevate the load to the carriage, 60 the carriage being held the while by the haul-back line 55.

Thereafter the line 2 is drawn in and the line 3 paid out, which opposite movements of the track lines operate the screw 31 and 65 toggle mechanism in the manner explained

to grip and secure the hauling rope 12 between 18 and 19 and prevent the load falling from the carriage. Thereafter the carriage is drawn along the track lines 2 and 3 by the hauling line 12 and when it arrives 70 at its destination the track lines 2 and 3 are moved in the opposite direction to that indicated by the arrows (A) and (B), by which opposite movement the screw 31 is drawn in and the clutch 18, 19 released 75 permitting the load to be lowered to the ground by the hauling rope 12.

Having now particularly described my invention, I hereby declare that what I claim as new and desire to be protected in 80 by Letters Patent, is:

1. A means for elevating a load to an overhead carriage and for securing it at any desired position of elevation, said means comprising the combination with parallel 85 track ropes susceptible of endwise movement in opposite directions, a carriage suitably supported to run on the track rope, a hauling line passing over sheaves on the carriage, a load hook connected to the line 90 adjacent its end, a clamp adapted to secure the hauling rope to the carriage, and means operative by endwise movement of the track ropes for securing and releasing the clamp.

2. A means for elevating a load to an 95 overhead carriage and for securing it at any desired position of elevation, said means comprising the combination with parallel track ropes susceptible of endwise movement in opposite directions, a carriage suitably supported to run on the track ropes, a hauling line passing over sheaves on the carriage, and connected to the carriage, a load hook in the bight of the line between its connection to the carriage and one of the 100 sheaves, a clamp adapted to secure the hauling rope to the carriage between the load hook and where the line passes to the hauling engine, and means operated by endwise movement of the track ropes for securing 105 and releasing the clamp.

3. A means for elevating a load to an overhead carriage and for securing it at any desired position of elevation, said means comprising the combination with parallel 115 track ropes susceptible of endwise movement in opposite directions, a carriage suitably supported to run on the track ropes, a hauling line passing over sheaves on the carriage and connected to the carriage, a 120 load hook in the bight of the line between its connection to the carriage and one of the sheaves, a clamp adapted to secure the hauling rope to the carriage between the load hook and where the line passes to the 125 hauling engine, and means operated by endwise movement of the track ropes for securing and releasing the clamp, said means comprising a screw rotatably mounted on the carriage and operable from one of the 130

track wheels, a nut threaded to fit the screw, and rotatable from another track wheel of the carriage, and means connected to the end of the screw whereby endwise movement 5 of it operates the clamp.

4. A means for elevating a load to an overhead carriage and for securing it at any desired position of elevation, said means comprising the combination with parallel track 10 ropes susceptible of endwise movement in opposite directions, a carriage suitably supported to run on the track ropes, a hauling line passing over sheaves on the carriage, and connected to the carriage, a load hook 15 in the bight of the line between its connection to the carriage and one of the sheaves, a clamp adapted to secure the hauling rope to the carriage between the load hook and where the line passes to the hauling engine, 20 and means operated by endwise movement of the track ropes for securing and releasing the clamp, said means comprising a screw rotatably mounted on the carriage and operable by a friction drive from one of the 25 track wheels, a nut threaded to fit the screw, and rotatable by a friction drive from another track wheel of the carriage, and means connected to the end of the screw whereby endwise movement of it operates the clamp.
5. A means for elevating a load to an overhead carriage and for securing it at any desired position of elevation, said means comprising the combination with parallel track ropes susceptible of endwise movement

in opposite directions, a carriage suitably 35 supported to run on the track ropes, a hauling line connected to the carriage intermediate its ends and passing around a sheave at the outer end of the carriage and over a sheave at the opposite end thereof, a sheave 40 carrying a load hook supported in the bight of the hauling line between the connection of the same to the carriage and the sheave at the outer end, a haul-back line connected to the carriage, a clamp bar secured to the 45 carriage between the hauling rope sheaves, a movable clamp bar adapted to press the hauling line into engagement with the fixed bar, toggle links connecting the movable bar to the carriage, a screw rotatably mounted 50 on the carriage, means for rotating the screw by a friction drive from one of the track wheels of the carriage while permitting endwise movement of the screw in the rotating means, a nut threaded to engage the 55 screw and susceptible of rotational movement but held against endwise movement, means for rotating the nut by a friction drive from a track wheel on the other track rope, a cross-head connected to the screw 60 in a manner permitting rotational movement in the connection, a lever pivoted to the carriage one end of which lever is connected to the cross-head, and means connecting the medial portion of the toggle links to the 65 lever.

In testimony whereof I affix my signature.

WILLIAM L. BARTON.
